DELAYED CONTROL TIME LOCK

William C. Miller, Canton, Ohio, assignor to Diebold Safe & Lock Co., Canton, Ohio, a corporation of Ohio

Application September 4, 1934, Serial No. 742,667

14 Claims. (Cl. 70—26)

This invention relates particularly to delayed control time-locks and means for preventing opening of a safe-door until a predetermined time has elapsed after the combination has been set for unlocking.

The invention is in the nature of an improvement upon the invention disclosed in the application of William C. Miller and Christopher W. Kuenzel, Serial Number 613,954, filed May 27th, 1932.

The invention is well adapted for use in connection with a combination lock equipped with chronometric mechanism which is energized during the manipulation of the dial in setting the tumblers to permit retraction of the locking bolt, or locking bolts, of the safe.

In the preferred embodiment, clock mechanism is employed, and the clock spring is wound in manipulating the dial. Also, in the preferred arrangement, the clock begins to run immediately after the winding operation is completed, and operates to withdraw, at the end of a predetermined period, an abutment, or dog, which serves to prevent the bolt-work from being withdrawn after the combination has been set for unlocking until the predetermined period of delay has elapsed.

In the application referred to above, a mechanism is disclosed which is provided with a timing gear located in the rear of the casing, this gear being actuated through the medium of a gear train likewise located in the rear portion of the casing. In accordance with the present invention, the winding-gear which is actuated during the manipulation of the dial to effect the winding of the clock-spring is itself equipped with means for withdrawing the abutment (the auxiliary means for preventing the withdrawal of the bolt). This expedient very greatly simplifies and cheapens the construction and renders the mechanism much more convenient.

The invention is illustrated in a preferred embodiment in the accompanying drawings, in which—

Fig. 1 represents a broken sectional view of a door equipped with a combination lock having applied thereto the improved time-mechanism; Fig. 2, a view taken as indicated at line 2 of Fig. 1, showing the front section of the casing and the combination lock-mechanism mounted therein; Fig. 3, a view taken as indicated at line 3 of Fig. 1, showing the rear section of the casing and the clock mechanism mounted therein, it being noted that these casing-sections and the mechanisms mounted therein are complementary to each other,

and it being further noted that Fig. 3 shows the position of the parts after the winding operation has been completed and when the setting-up of the combination is just about complete, as illustrated in Fig. 2; Fig. 4, a broken horizontal sectional view of the casing, exposing the mechanisms; Fig. 5, a broken front view of the clock-mechanism showing the relation of the parts at about the time the winding operation begins, it being noted that the pin which appears on the 10 disk of the combination lock-mechanism fixed to the spindle, as shown in Fig. 2, is indicated by dotted lines in Fig. 5, engaging a slot in the disk which carries the winding-pawl; Fig. 6, a view similar to Fig. 5, but showing the position of the 15 parts at the instant the winding-pawl is slipping past the stud on the winding-gear at the conclusion of the winding operation; Fig. 7, a similar view, showing the disk and pawl appearing in Fig. 6 removed and also showing the winding 20 gear removed, but indicated in dotted lines, this view indicating the position of a ring-like lever which is to serve to lift the abutment which blocks the path of the pin (shown in dotted lines) which is carried by the bolt-actuating member, 25 this pin appearing in full lines in Fig. 2, near the pivot of the bolt-actuating member; Fig. 8, a view similar to Fig. 7, showing the abutment in retracted, or raised position; Fig. 9, a view similar to Fig. 8 after the clock has operated a sufficient 30 length of time to permit the abutment to drop to obstructing position; and Fig. 10, a sectional view taken as indicated at line 10 of Fig. 6, illustrating the manner in which the winding gear and attendant parts are mounted on the clock-frame. 35

In the illustration given, A designates a door; B, a casing-section secured to the rear face of the door, as by means of screws 1, said casing-section containing a combination lock-mechanism, including a spindle B' which extends through the door and is equipped with an actuating knob B² and a dial B³, the latter associated with a dial-ring B⁴ which is secured to the door in the usual manner, as by means of screws (not shown); C, a casing-section which is complementary to the 45 casing-section B, and which is secured thereto by means of screws 2 which may extend through the casing-section C and into tapped openings with which the front casing-section B is provided in the lugs 3, shown in Fig. 2; and C', clock-mechanism mounted in the rear casing-section C, this 50 clock-mechanism being adapted to be wound in manipulating the combination lock-mechanism, and serving, in turn, to control the withdrawal of the bolt of the combination lock-mechanism. 55

The combination lock-mechanism is shown as comprising a main locking-bolt 4; a bolt-actuating member 5 connected with the bolt by a pivot 5^a; a rear disk 6 fixedly secured on the rear end 5 of the spindle B'; and tumbler-disks 7 mounted on the spindle in the usual manner. These parts are of the usual construction and arrangement. The member 5 is equipped with a forwardly projecting bar or pin 5^b which is adapted to ride upon the tumbler-disks and at the proper time enter the slots indicated at 7^a. The member 5 is provided, also, with the usual lug 5^c which is adapted to drop into a recess 6^a with which the disk 6 is provided, it being understood that the bolt 4, in this construction, is actuated through the medium of the member 5 when the spindle B' is turned to actuate the disk 6, assuming the lug 5^c to be in engagement with the recess 6^a.

The member 5 is shown equipped with a stud D whose path normally is obstructed by a withdrawable abutment actuated by the clock-mechanism; and the disk 6, which is fixed to the spindle B', is shown equipped with a pin E which is adapted to actuate the winding-gear of the clock-mechanism during manipulation of the dial.

In Fig. 5, the position of the stud D and the position of the pin E are indicated by dotted lines.

The clock-mechanism comprises a frame 8 which is secured in the casing-section C, as by means of screws 8^a; a spring-housing 9 is suitably mounted on the frame, through which extends the usual main shaft 9^a which has fixed on its front end a pinion 9^b; 10, a winding gear which serves also as a carrier for an abutment-retracting device, the gear 10 being connected through an idler pinion 11 with the pinion 9^b; 12, an auxiliary locking-device, guard, or dog, which normally obstructs the path of the stud D, the member 12 having an arm 12^a supported on a pivot 12^b (Fig. 7), carried by the frame 8, and the member 12 being equipped with a cam arm 12^c; 13, (see Figs. 5-10) a short journal-member upon which the winding-gear 10 is journaled, this member carried by the frame 8; 14, a ring-like cam-lever journaled on the head-portion of the member 13 and equipped with an actuating arm 14^a and a cam-lug 14^b adapted to actuate the arm 12^c; 15, a pawl-carrying disk eccentrically mounted (with reference to the winding gear 10) on a pivot-screw 15^a which serves also to secure the journal 13 to the frame-member 8; and 16, a winding-pawl carried by the disk 15, said pawl being connected by a pivot-screw 16^a to the disk 15 and equipped with a spring 16^b.

The disk 15 is equipped with a stud 15^b which limits the movement of the pawl 16 in one direction.

The winding gear 10 is provided with a forwardly projecting stud 10^a which is engaged by the outer end of the pawl 16 during the winding operation. Because of the eccentric journaling of the disk 15 with relation to the winding-gear, the pawl 16, at the end of the winding stroke, slips past the stud 10^a. The operation will be understood by referring to Figs. 5 and 6, the position in Fig. 6 corresponding with the instant that the pawl 16 is to spring past the stud 10^a. A moment later, the spring 16^b will have moved the butt end of the pawl away from the stud 15^b (compare Fig. 3).

The winding gear 10 is provided with a rearwardly projecting stud 10^b (Fig. 7) which, during the winding operation, returns the ring-form lever 14 to the operative position; also, the winding gear is provided with a series of tapped

perforations indicated at 10^c. Any one of these perforations may receive a stud or screw 10^d which serves to actuate the lever 14 during the working stroke thereof. The stud 10^d may be set to time the withdrawal of the auxiliary locking-device 12, as desired. In the illustration given, the stud 10^d may be set to time the release to a period of 10 minutes up to 30 minutes, the spacing of the perforations corresponding with the 5-minute period.

In Fig. 8, the abutment 12 has been lifted to a point which clears the path of the stud D on the member 5 of the combination lock-mechanism. During the lifting of the member 12, the cam-tooth 14^b works on a surface 12^d of the cam arm of the member 12. For a short period, say 2 or 3 minutes thereafter, the arm is held out of the path of the stud D. During this short period, the combination lock may be manipulated to withdraw the bolt 4. Finally, the tooth 14^b passes the cam arm and permits the auxiliary locking-device 12 to drop again (see Fig. 9) into the path of the stud D, so that if the bolt 4 has not been retracted in the meantime, it cannot be retracted without first operating the delayed time-control again.

Referring to Fig. 10, it will be noted that the frame 8 is equipped with a forwardly projecting dowel-pin 17 which enters a perforation with which the journal-member 13 is provided. Also, it will be noted that the head-portion of the journal 13 serves to space the winding gear 10 from the frame, and the ring-form lever 14 is located in the intervening space.

The clock-work is, in the main, of the usual construction. The pinion 9^b is mounted on the forward end of the shaft 9^a which extends through the main spring casing 9. As is well understood, one end of the spring (not shown) is secured to the shaft 9^a and the other end is secured to the casing 9. At the rear end, the shaft 9^a is equipped with a gear 18 which turns idly under a pawl 19 during the winding operation. Later, in the operation of the clock-mechanism, the gear 18 serves through the medium of a pawl 20 to actuate a freely journaled gear 21 which drives a gear train 22 controlled by balance wheels or escapements 23. Any suitable escapement may be employed. In the illustration given, two escapements are employed, these escapements being connected through a differential gear device 24. The double escapement device just referred to is described and claimed in the application of William C. Miller and Paul M. Hawkins, Serial Number 688,692, filed September 8, 1933.

The operation may be described briefly:

In the dialing operation for placing the combination lock mechanism in condition to unlock the bolt 4, the winding gear train 10, 11, and 9^b is actuated in one direction to effect winding of the clock-spring. Thus, the stud E on the disk 6 which is fixed to the rear end of the spindle B' engages a slot 25 in the winding-disk 15. When the knob B² is turned clockwise, the disk 6 turns in the same direction (but counter-clockwise as viewed in Fig. 2). Thus, the winding-disk 15 is turned clockwise, as viewed in Fig. 5, and the winding-gear is turned by the pawl 16 engaging the cam stud 10^a until, by reason of the eccentric mounting of the member 15, the pawl slips past the stud 10^a. Subsequent manipulations of the dial will not affect the clock-mechanism, inasmuch as the full winding is effected during one right turn of the knob B². 75

Upon winding, the clock immediately begins to run, the winding gear 10 being turned counter-clockwise. The lever 14 is not actuated until the stud 10^d carried by the winding gear comes 5 into engagement with the arm 14^a (Fig. 7). When this occurs (Fig. 8) lever 14 is turned to effect retraction of the abutment 12, thus freeing the stud D, so that the bolt 4 may be retracted. While the lever 14 is turning from the 10 position shown in Fig. 8 to the position shown in Fig. 9, the bolt 4 may be retracted at any time before the abutment 12 drops again to the obstructing position. The clock continues to operate until the arm 14^a engages a stop-stud 26 15 with which the frame 8 is equipped. In the next winding operation, the stud 10^b on the winding gear returns the lever 14 to the operating position shown in Fig. 7, it being noted that the cam arm 12^c is so formed as to permit the tooth 20 14^b to pass the cam arm.

If it be desired to vary the period of delay, the screw 10^d may be adjusted to a new position on the winding-gear 10. The casing-sections may be readily separated to enable such adjustment 25 to be made, it being necessary only to remove the two screws indicated by the numeral 2. It is noted that the front casing-section B has the guide for the bolt 4 recessed as indicated at 27 (Fig. 2); and the casing-section C (Fig. 3) is 30 provided with a tongue 28 which fits into the recess 27.

From the description given, it will be evident that the mechanism has been improved and simplified by making use of the expedient of utilizing 35 the winding-gear train as a means for effecting, in the reverse movement, withdrawal of the auxiliary locking device 12. In the winding operation the member 10 is actuated clockwise, as indicated by the arrow in Fig. 5. When the member 40 10 is actuated by the clock-spring, however, its movement is counter-clockwise, and during this reverse movement the auxiliary locking-device is retracted. In the construction illustrated, the winding gear-train is located at the front 45 side of the frame of the clock-mechanism and is immediately accessible upon removing the casing-section C from the casing-section B. Thus, the means for actuating the abutment 12 is located at the front side of the rear casing-section. 50 The foregoing detailed description has been given for clearness of understanding only, and no unnecessary limitations should be understood therefrom, but the appended claims should be construed as broadly as permissible, in view of 55 the prior art.

What I regard as new and desire to secure by Letters Patent is:

1. Locking mechanism comprising a closure-locking bolt; main locking means comprising a 60 combination lock controlling actuation of said bolt and equipped with tumblers adapted to be brought to position to permit the unlocking operation by manipulation of the dial; auxiliary means for preventing withdrawal of the bolt; clock mechanism adapted to effect release of said auxiliary means after a predetermined period, said mechanism including a winding gear; a member 65 movably associated with said gear adapted to effect the release of said auxiliary means; means mounted on said gear for actuating said last-mentioned member; and means interposed between the combination lock and said gear adapted to turn said gear in a direction to wind the 70 75 clock-spring in the manipulation of the dial.

2. Locking-mechanism as specified in claim 1, in which the means for actuating said gear to wind the clock-spring comprises a disk pivotally related to said gear, a winding-pawl carried by said disk, a stud carried by said gear adapted to be actuated by said pawl, and means carried by the combination lock for actuating said disk. 5

3. In combination: a combination lock including a closure-locking bolt; clock-mechanism equipped with an auxiliary locking-device for 10 preventing retraction of said bolt; a winding-gear journaled on the frame of the clock-mechanism and equipped with a winding disk carrying a winding-pawl; a stud on said gear adapted to be actuated by said pawl in the winding operation; and means carried by the combination lock-mechanism serving to actuate said winding disk during the manipulation of the dial to bring the combination to the unlocking position. 15

4. In combination: a combination lock provided with a closure-locking bolt; clock-mechanism; a winding gear-train serving to wind the spring of said clock-mechanism and then to be actuated in a reverse direction by said spring; a winding-disk journaled eccentrically on one of 25 the gears of said train and equipped with a winding pawl which coacts with a stud carried by such gear during a portion of the rotation of said winding-disk; an auxiliary locking-device for preventing retraction of said bolt; and means carried by said combination lock serving to actuate said winding disk when the dial is manipulated to bring the combination lock tumblers to the 30 unlocking position.

5. A structure as specified in claim 4, in which 35 the winding-gear train is interposed between the combination lock and the frame of the clock-mechanism.

6. A structure as specified in claim 4, in which the winding gear train and the auxiliary locking-device are mounted at the front face of the frame 40 which carries the clock-mechanism.

7. In combination: a combination lock provided with a closure-locking bolt; clock-mechanism mounted back of said combination lock; a 45 device actuated by the combination lock in the manipulation of the dial thereof to bring the parts to the unlocking position; winding mechanism mounted at the front side of the frame of said clock-mechanism adapted to be actuated by 50 said device to effect winding; and an auxiliary locking-device pivotally mounted on the front portion of the clock frame adjacent said winding mechanism and actuated thereby in a reverse movement of the winding mechanism, said 55 auxiliary locking-device serving to obstruct retraction of said locking bolt until retracted through the medium of said winding mechanism.

8. In combination: a combination lock, including a closure-locking bolt; clock mechanism 60 mounted back of said combination lock; a winding-member actuated by said combination lock in the dialing operation; an auxiliary locking-device adapted to prevent retraction of said locking bolt; and a winding gear-train, which includes a gear journaled on the frame of the clock-mechanism, a winding disk eccentrically journaled with relation to said gear, a pawl pivotally mounted on said winding disk coacting 65 with a stud carried by said gear to effect winding, a cam-lever pivotally related to said gear and serving to effect retraction of said auxiliary locking device when the winding mechanism is driven in a reverse direction by the clock-spring, 70 75

and a timing-stud carried by said gear adapted to actuate said cam-lever.

9. In combination: locking-mechanism comprising a closure-locking bolt; main locking means controlling the movement of said bolt; auxiliary means for preventing withdrawal of the bolt; time mechanism adapted to effect retraction of said auxiliary means and after an interval to permit the auxiliary means to return to bolt-obstructing position; and means actuated in the operation of said main locking-means serving to energize said time-mechanism.

10. Locking mechanism comprising: a closure-locking bolt; main locking means comprising a combination lock controlling actuation of said bolt and equipped with tumblers adapted to be brought to position to permit the unlocking operation by manipulation of the dial; auxiliary means for preventing withdrawal of the bolt; time mechanism adapted to effect release of said auxiliary means after a predetermined period and after a further period to permit said auxiliary means to return to the bolt-obstructing position; and means actuated by the combination lock in the operation of dialing and manipulating the tumblers for energizing said time mechanism.

11. In mechanism of the character set forth: a frame; a clock mounted therein; a journal secured to the frame; a winding gear on said journal; a cam-lever mounted on said journal; means carried by said gear for actuating said cam-lever; and a winding-disk eccentrically journaled with respect to said first-mentioned journal and equipped with a winding pawl coacting with a stud carried by said gear.

12. In a device of the character set forth: a closure-locking bolt; an auxiliary locking-member for obstructing movement of said bolt equipped with a cam arm; a journaled cam lever coacting with said cam arm; a gear equipped with studs for actuating said cam-lever in both directions; and a winding-disk eccentrically journaled with relation to said gear and equipped with a winding pawl coacting with a stud carried by said gear.

13. In combination: a combination lock, including a closure-locking bolt, said combination-lock carrying a winding member; an auxiliary locking-device for preventing retraction of said bolt; time mechanism having means for retracting said auxiliary locking device and after a short interval permitting it to return to bolt-obstructing position, said time-mechanism being equipped with means actuated by the winding-member of the combination lock serving to energize the time mechanism.

14. A device as specified in claim 13, in which the time-mechanism is equipped with a winding gear and an associated cam-lever actuated in one direction by said gear during the winding operation and in the other direction by said gear when driven by the clock spring, and in which said auxiliary locking-device is equipped with a cam arm actuated by said cam-lever to release the auxiliary locking-device and then permit return thereof to bolt-obstructing position.

WILLIAM C. MILLER.
